By Attorneys,

UNITED STATES PATENT OFFICE.

BENNO F. JANCKE, OF BROOKLYN, NEW YORK, ASSIGNOR TO EASTERN LABORATORIES, INC., OF NEW YORK, N. Y., A CORPORATION OF NEW YORK.

VIOLET-RAY GENERATOR.

Application filed January 31, 1923. Serial No. 616,091.

To all whom it may concern:

Be it known that I, BENNO FREDERICK JANCKE, a citizen of the German Republic, and residing at Number 1406 Pacific Street, 5 in the borough of Brooklyn, city and State of New York, have invented certain new and useful Improvements in Violet-Ray Generators, of which the following is a specification.

10 This invention relates to violet ray generators of the applicator type, that is, designed primarily for therapeutic use, and aims to provide improvements therein.

15 The invention provides a device of the character referred to, of simple construction, capable of ready and economical manufacture, and hence capable of sale at a popular price.

An embodiment of the invention is illustrated in the accompanying drawings, in which—

Figure 1 is a longitudinal sectional view of the generator showing a so-called applicator connected thereto.

25 Fig. 2 is a view partly in section and partly in elevation of a spool or framework, in which the various electrical parts are conveniently mounted.

Fig. 3 is a diagrammatic view showing 30 the electrical construction and arrangement.

Referring to said drawings, numeral 10 designates a spool or framework, having a socket or other means of attachment 12 in one end, adapted to hold an electrode 14 of the applicator type therein and within which is generated the violet ray to which the therapeutic action of the device is due. This spool 10 is adapted to fit within a tube or sleeve 16, and the spool is conveniently 35 formed with a head 18 at one end, which closes one end of said tube, said head 18 being preferably slightly tapered as indicated at 19, so as to enter the tube easily and make a tight fit therewith, said head also 40 being conveniently formed with a shoulder 20 against which the end of the tube 16 abuts. Behind the head 18 the spool is of reduced diameter, as indicated at 25, 26, to afford space within the tube 16 for the primary and secondary windings 27, 28 of the high-tension transformer or spark coil 30, and for a choke-coil or inductance 32 and a condenser 34. The end 37 of the spool is 45 conveniently of enlarged diameter, corresponding to the inside diameter of the tube

16, and serves to support the said tube, and also to form a support or base for the interrupter or sparking electrodes 40, 41. The spool 10 is also preferably provided with an annular enlargement 44 about midway between the head 18 and the opposite enlargement 37, and of a diameter corresponding to that of the tube 16, which serves to support the middle portion of said tube and divides the space between the ends of the 65 spool.

On the end enlargement 37 there is conveniently provided two posts 46 which support a bridge piece 47, and preferably also a disc 48, of insulating material. The sparking electrode 41 is supported by said bridge piece 47, the said electrode being preferably mounted on a threaded rod 49 by means of which the distance apart of the electrodes 40, 41 may be adjusted and the intensity 75 of the violet ray controlled. The tube 16 preferably extends beyond said disk 48, so as to close the adjacent end of said tube and consequently enclose the parts on the end portion 37 of said spool. 80

The spool 10 is preferably bored at each end, as indicated at 50, 51, the former serving for the reception of an iron core for strengthening the magnetic effect of the choke-coil 32. The recess 51 serves for receiving a tang 54 on a conducting thimble 55, and connection of the end of the secondary winding 28, to the tang 54 is conveniently made through a small hole 57. 85

The electrical arrangement is conventional, the secondary 28 being connected to the applicator 14, at one end as indicated at 60, Fig. 3, and grounded on the primary 27, as indicated at 61. The primary is connected to the lead wire 70 through a conductor 71 on one side, and to lead wire 73 through choke-coil or inductance 32, interrupter or sparking electrodes 40, 41, and conductor 74 on the other side. The condenser 34 is placed in shunt with 90 the primary 27 by wires 76, 77, 78 leading to conductor 71, and to the interrupter 40, 41. An oscillatory discharge is produced between the sparking electrodes 40, 41, which sets up oscillations in the primary 27, thereby inducing high-tension currents in the secondary 28, thereby producing the violet-ray discharge in the rarefied applicator tube 14. 100

The inventive idea may receive other em- 110

bodiments than that herein specifically illustrated and described.

What I claim is:

1. A violet ray generator, comprising a 5 spool or frame, having portions of reduced diameter, coils and a condenser on said reduced portion, and a tube adapted to slip onto said spool and cover said coils and condenser, said spool having portions having a diameter corresponding to that of said tube for supporting the same.

2. A violet ray generator, comprising a spool or frame, having portions of reduced 15 diameter, coils and a condenser on said reduced portion, and a tube adapted to slip onto said spool and cover said coils and condenser, said spool having portions having a diameter corresponding to that of said tube for supporting the same, one of 20 said tube-supporting portions constituting a head and having an applicator-socket therein.

3. A violet ray generator, comprising a spool or frame, having portions of reduced 25 diameter, coils and a condenser on said reduced portion, and a tube adapted to slip onto said spool and cover said coils and condenser, said spool having portions having a diameter corresponding to that of said 30 tube for supporting the same, said tube being an open-ended tube of substantially uniform diameter.

4. A violet ray generator, comprising a spool or frame, having portions of reduced 35 diameter, coils and a condenser on said reduced portion, and a tube adapted to slip onto said spool and cover said coils and condenser, said spool having portions having a diameter corresponding to that of said 40 tube for supporting the same, said tube being an open-ended tube of substantially uniform diameter, one of said tube-supporting portions constituting a head and having an applicator-socket therein.

45 5. A violet ray generator, comprising a spool or frame, having portions of reduced diameter, coils and a condenser on said reduced portion, and a tube adapted to slip onto said spool and cover said coils and 50 condenser, said spool having portions having a diameter corresponding to that of said tube for supporting the same, said generator further comprising an interrupter supported on one of said tube-supporting sections.

55 6. A violet ray generator, comprising a spool or frame, having portions of reduced diameter, coils and a condenser on said re-

duced portion, and a tube adapted to slip onto said spool and cover said coils and condenser, said spool having portions having a diameter corresponding to that of said tube for supporting the same, said generator further comprising an interrupter supported on one of said tube-supporting sections, said tube supporting portion being situated inward from an end of said tube, whereby the parts thereon are encased by said tube.

7. A violet ray generator, comprising a spool or frame, having portions of reduced 70 diameter, coils and a condenser on said reduced portion, and a tube adapted to slip onto said spool and cover said coils and condenser, said spool having portions having a diameter corresponding to that of said tube for supporting the same, said generator further comprising an interrupter supported on one of said tube-supporting sections, said tube supporting portion being situated 75 inward from an end of said tube, whereby the parts thereon are encased by said tube, said tube-supporting portion further having posts thereon and a disc on said posts beyond said interrupter, adapted to close the end of said tube.

8. A violet ray generator, comprising a spool or frame, having portions of reduced diameter, coils and a condenser on said reduced portion, and a tube adapted to slip onto said spool and cover said coils and condenser, said spool having portions having a diameter corresponding to that of said tube for supporting the same, said spool having a longitudinal recess therein, and an iron core therein for strengthening the field 90 of one of said coils.

9. A violet ray generator, comprising a spool or frame, having portions of reduced diameter, coils and a condenser on said reduced portion, and a tube adapted to slip onto said spool and cover said coils and condenser, said spool having portions having a diameter corresponding to that of said tube for supporting the same, one of said tube-supporting portions constituting a head 100 and having an applicator-socket therein, said spool having a thimble in said head, and a recess extending into the reduced portion of said spool through which connection between a coil on said spool and said thimble 105 may be made.

In witness whereof, I have hereunto signed my name.

BENNO F. JANCKE.
